United States Patent Office

Des. 194,270
Patented Dec. 25, 1962

194,270

SLED

Charles Dunn, 19 Clover St., Pawtucket, R.I.

Filed June 25, 1962, Ser. No. 70,660

Term of patent 14 years

(Cl. D34—15)

FIG. 1

FIG. 2

FIG. 3

FIG. 4

FIG. 5

FIG. 1 is a perspective view of a sled showing my new design;

FIG. 2 is a bottom view thereof;

FIG. 3 is a front view thereof, on an enlarged scale;

FIG. 4 is a side elevational view thereof; and

FIG. 5 is a rear view thereof, on an enlarged scale.

I claim:

The ornamental design for a sled, substantially as shown.
